[57] CLAIM

The ornamental design for the brush for grooming animals, as shown and described.

DESCRIPTION

FIG. 1 is a top perspective view of a brush for grooming animals showing my new design;

FIG. 2 is a bottom perspective view thereof;

FIG. 3 is a bottom plan view thereof;

FIG. 4 is a side elevational view as seen from the right of FIG. 3;

FIG. 5 is a top plan view thereof;

FIG. 6 is an elevational view of the side opposite that shown in FIG. 4; and,

FIG. 7 is an end elevational view thereof, the opposite side being a mirror image.
